Inventor:

Charles C. Montague.
By J. S. Duffie,
Attorney.

UNITED STATES PATENT OFFICE.

CHARLES CARTER MONTAGUE, OF AUGUSTA, ARKANSAS.

BALE-BAND TIGHTENER.

SPECIFICATION forming part of Letters Patent No. 292,249, dated January 22, 1884.

Application filed June 22, 1883. (No model.)

To all whom it may concern:

Be it known that I, CHARLES CARTER MONTAGUE, a citizen of the United States, residing at Augusta, in the county of Woodruff and 5 State of Arkansas, have invented certain new and useful Improvements in Toggle-Levers or Bale-Band Tighteners or Bale-Rebinders; and I do declare the following to be a full, clear, and exact description of the invention, such as will 10 enable others skilled in the art to which it app pertains to make and use the same, reference being had to the accompanying drawings, and to the letters and figures of reference marked thereon, which form a part of this specification.

15 My invention relates to bale-band tighteners and rebinders; and it consists in a lever having four hooks and one roller in connection with a chain, hereinafter more particularly described.

20 In the accompanying drawings, Figure 1 is a face view of my invention, showing the lever A, the hooks, and roller. Fig. 2 shows the chain E around the end of a bale and the manner of applying the hooks. Fig. 3 shows the 25 manner of taking the second hold of the chain.

My invention is described as follows: I take 30 a beam of strong seasoned wood, about three or four inches square, and from four to six feet long. Commencing about two feet from one end, I draw the beam down for the handle B. On the large end A, I secure a roller, F, ex- 35 tending the full width of the lever. This roller is journaled on a shaft, f, securely riveted in braces or arms f', one on either side of the lever, and secured thereto by rivets. This roller is to prevent the end of the lever from catching in and tearing the covering of the bale. When the end of the lever strikes the bale, the 40 roller turns on the shaft f and allows the lever to work freely. To the lower end of this lever I secure two hooks or claws, a a'. These hooks are pivoted at their upper ends on either edge of the lever, between the extended ends b b of 45 two strong iron plates, C, which plates embrace the lever, one being on the upper and the other on the lower side of the lever, and are securely riveted thereto. About a foot or eighteen inches from the end A of the lever, and above 50 the lower plates, C, are plates D, which also embrace the lever, one being on the upper and the other on the lower side of the same; but

these plates D may slide up and down and may be secured at any distance from the end by a pin, d, passing through the middle hole, d', in 55 the plates D, and through either of the holes d'' in the lever. Between the ends of these plates D, and on either edge of the lever, is pivoted, at point d'', two other and larger hooks, b b'. These plates D, and consequently the 60 hooks b b', may be moved up or down on the lever and secured at either of the holes d'', thus shifting the fulcrum at will.

In operating my invention, I first put a strong link-chain, E, around the bale, Fig. 2, 65 at the point where the band has broken or become loose. In the lower end of the chain I insert short hook a'. Then raising the handle B until it is almost perpendicular, I insert the long hook b into the highest link it will reach. 70 This makes the fulcrum at plates D. Then I pull down on the lever until the handle B comes to the ground. Then, while the hooks are still fast, I insert long hook b' into the lowest link it will reach and short hook a into the 75 highest link it will reach, (see Fig. 3,) and as I raise the handle short hook a' and long hook b are released, and the fulcrum is, as before, at plates D. When the handle is again elevated, as in Fig. 2, I again insert long hook b 80 and short hook a' into the chain, and pull down as before, and so on until the bale is sufficiently compressed. Then I tighten the band and move my chain to the next loose one.

Having thus described my invention and the 85 manner of operating it, what I claim as new, and desire to secure by Letters Patent, is—

A lever, A, having journaled on its lower end, between arms f', securely riveted, one on the lower and the other on the upper side of 90 said lever, roller F, hooks a a', pivoted in the ends b b of plates C, and hooks b b', pivoted in the ends of plates D, which plates embrace the lever, and capable of being secured at any one of the holes d'' in the lever by pin d, in 95 combination with link-chain E, substantially as shown and described, and for the purposes set forth.

In testimony whereof I affix my signature in presence of two witnesses.

CHARLES CARTER MONTAGUE.
